UNITED STATES PATENT OFFICE.

REASON C. THARP, OF OSCEOLA, MISSOURI.

COMBINED AIR INLET AND EXHAUST VALVE.

1,259,805.

Specification of Letters Patent.

Patented Mar. 19, 1918.

Application filed June 21, 1917. Serial No. 176,202.

To all whom it may concern:

Be it known that I, REASON C. THARP, a citizen of the United States, residing at Osceola, in the county of St. Clair and State 5 of Missouri, have invented certain new and useful Improvements in Combined Air-Inlets and Exhaust-Valves, of which the following is a specification, reference being had therein to the accompanying drawing.

10 This invention relates to a combined air inlet and exhaust valve designed particularly for use in connection with gasoline and like fuel tanks for the supply of air to the tank to place the body of liquid fuel therein under a desired pressure, for feed to the motor, 15 burner, or element to be supplied with fuel.

The primary object of the invention is to provide a combined air inlet and exhaust valve, through which air may be supplied to 20 the tank through the medium of an ordinary air pump, and by means of which the air may be quickly exhausted from the tank when desired.

A further object of the invention is to provide a combination valve of the character described which is adjustable to be conveniently set for an air feeding or air exhaust 25 action at will.

A still further object of the invention is 30 to provide a valve of the character described which is simple of construction, reliable and efficient in action, inexpensive of production, and adapted to be applied for use either to the body of the tank or to the usual cap or 35 closure employed to seal the filling opening.

With these and other objects in view, the invention consists of the features of construction, combination and arrangement of parts hereinafter fully described and 40 claimed, reference being had to the accompanying drawing, in which:—

Figure 1 is a vertical section through a portion of a fuel tank and the improved valve device, said valve device being shown 45 in connection with the closure cap for the filling opening.

Fig. 2 is a view in elevation of the cap with the valve applied thereto.

Fig. 3 is a top plan view of the same.

50 Fig. 4 is a side elevation of the rotary plug valve element.

Fig. 5 is a sectional view of the bushing.

Referring to the drawing, 1 designates a portion of a body of a gasoline or other 55 liquid fuel tank, which is provided with a

threaded filling opening 2 for the reception of the usual sealing cap or closure 3. The valve is shown in the present instance as applied to and forming a part of this cap, although it is to be understood that it may 60 be made independently of the cap and applied to any suitable part of the body of the tank.

The cap 3 comprises, in the present example, the body member of the valve device, 65 and its cap is shown as provided in its upper portion with a central recess 4, at diametrically opposite sides of which are arranged lugs 5', which may be employed as finger pieces or for engagement with a spanner 70 wrench or like tool to adapt the cap to be applied and removed with facility.

In its bottom the cap 3 is provided with an opening 5 and fitted within this opening 75 is a bushing 6, which may be threaded or otherwise secured in position. This bushing 6 is formed with a tapered passage 7, extending vertically through the same and communicating at its upper end with the recess 4, said passage 7 forming a conical seat for 80 a conical or tapered plug valve 8.

The valve 8 extends through and above and below the passage 7, and is provided upon its lower projecting end with an opening 9 for the passage of a transverse pin or 85 similar abutment 10 confining in position a washer or abutment 11 between which and the bottom of the bushing is disposed a coiled spring 12, said spring serving by its expansive action to draw downward upon the plug 90 valve 8 and to at all times hold it properly seated in the tapered passage 7, to effect an air and liquid tight seal.

The valve 8 is provided with an upwardly extending nipple 13 which is externally 95 threaded for the reception of a sealing cap 14, and said valve is formed with a longitudinally extending bore or passage 15 opening at its upper end through the nipple and at its lower end through a lateral duct 100 16 into the body of the tank, through the side of the valve, whereby air under pressure may be supplied through said bore or passage to the tank by means of a pump applied to the nipple 13. The bore or passage 16 is 105 controlled by means of a Shraeder or like type of spring controlled check valve, generally designated by 17, having an upwardly projecting plunger stem 18 which is depressed when the pump is applied to unseat 110

the valve for the flow of air to the tank, the valve at all other times automatically closing to hold and confine the air so introduced.

Formed in the bushing 6 is an air vent 5 groove or channel 19, which affords communication between the tank and passage 7, and formed in one side of the valve 8 is a coacting air vent groove or channel 20, designed to afford communication between 10 the groove 19 and the recess 4, and consequently with the atmosphere, so that when said grooves are in alinement and communication with one another the air contained within the tank may exhaust rapidly to the 15 atmosphere. Projecting from the upwardly extending portion of the valve 8 are diametrically disposed operating arms or finger pieces 21, whereby said valve may be turned or rotated in its seat, in such a manner that 20 the valve may be set for an air supplying and charging action alone, or may be turned to bring the grooves 19 and 20 into register for an air exhaust action. The arms 21 are provided with beveled end portions 22 to 25 engage the beveled ends 23 of the lugs 5', whereby the arms and lugs are adapted to form stops to limit the rotary movement of the valve to an extent not greater than 180° or a half revolution, and to prevent 30 movement of the valve beyond predetermined positions.

Figs. 1 and 3 show in full lines the valve disposed in the exhaust position, in which position the beveled ends of the arms 21 engage the beveled ends of the lugs 5', thus serving as means for indicating that the grooves 19 and 20 are in register, whereby the exhaust of air from the tank to the atmosphere will be permitted. The valve may 40 be reversed, however, or turned in one direction only to a position in which the ends of the arms 21 abut against the reverse sides of the lugs 5', as shown in dotted lines in Fig. 3, whereby the valve is disposed in such a 45 position that the grooves 19 and 20 are out of register, so that the passage 7 will be sealed against the exhaust of air, while permitting air to be introduced through the bore or passage 15. When disposed in either 50 operative position it will be evident that the force of the spring 12, while serving to hold the valve seated, will also tend to hold it from rotary movement, whereby the valve will be held positively against displacement 55 when adjusted to either working position.

It will thus be understood that the invention provides a valve device which may be conveniently applied to the closure cap of the filling opening of the tank, but may also 60 be applied to any other suitable portion of the tank, and that when the valve is arranged in position for use, it may be set either for an air introducing or an air exhaust action. Hence the tank may be supplied with a charge of air under pressure 65

acting upon the surface of the body of gasoline or other fuel for a feeding action, or may be set to permit the air to be quickly exhausted to the atmosphere. When the tank is not charged with air the valve 70 may be also disposed in an exhaust position to permit any fumes or vapor to escape so that safety may be secured. It will be observed that the exhaust and check valve device are combined in unitary form, thus 75 simplifying the construction of the device and adapting the same to be manufactured and sold at a comparatively low cost.

Having thus fully described my invention, I claim:

1. A combined air charging and air exhaust valve for the purpose described, embodying a rotary valve member having a vent passage upon its exterior surface for controlling the exhaust of air and having an 85 air feed passage extending therethrough, and a check valve controlling said air feed passage.

2. A combined air charging and exhaust valve for the purpose described, comprising 90 a valve body, a valve member movably mounted in the body about an axis extending longitudinally thereof for adjustment to open and close an exhaust port, said valve member being provided with an air charging passage, and a check valve controlling 95 said charging passage.

3. A combined air charging and exhaust valve for the purpose described, comprising a body having a vent passage, a rotary valve 100 member having a coöperating vent passage, and also having an air feed passage separated from said coöperating vent passage, and a check valve carried by said valve member and controlling said feed passage. 105

4. A combined air charging and exhaust valve for the purpose described, comprising a body having a vent passage, a rotary valve device having a coöperating vent passage extending longitudinally and upon the exterior surface thereof, and provided with an air feed port, a check valve carried by said valve member and controlling said air feed port, and means for limiting the rotary movements of the valve member to vent establishing and vent cut off positions. 110

5. A combined air charging and exhaust valve including a bushing having a longitudinal bore provided with a vent passage, a rotary valve device mounted in said bushing and operable about an axis extending longitudinally thereof, said valve device having spaced feed and exhaust ports, the latter being adapted for communication with said vent passage, and means in said 120 feed port controlling the passage of air therethrough.

6. A combined air charging and exhaust valve including a body having a recess and an opening formed therein, stop lugs pro- 125

jecting into said recess, a bushing in said opening and having a vent passage, a rotary valve device mounted in said bushing and a vent passage adapted for communication with the first named vent passage, and also having an air feed passage, a check valve controlling said air feed passage, and opposed operating arms extending from said valve device into said recess and en-

gageable with said lugs to limit the rotary ¹⁰ movement of said valve device to exhaust and feeding positions.

In testimony whereof I hereunto affix my signature in the presence of two witnesses.
